UNITED STATES PATENT OFFICE.

FRANCIS DIXON, OF LYNN, ASSIGNOR TO HIMSELF AND MOSES SWEETSER
OF NEWBURYPORT, MASSACHUSETTS.

IMPROVEMENT IN THE MANUFACTURE OF CIGAR-WRAPPERS.

Specification forming part of Letters Patent No. 25,604, dated September 27, 1859.

To all whom it may concern:

Be it known that I, FRANCIS DIXON, of Lynn, in the county of Essex and State of Massachusetts, have invented a new and useful Manufacture of Tobacco-Wrappers or Outside Coverings Used in Making Cigars; and I do hereby declare that the same is fully described in the following specification.

It is well known that the external covering of a cigar, or what is usually termed the "wrapper" thereof, has been made by taking tobacco in the natural state of its leaf and winding it about the internal part or filling. In the process of making cigars more or less of the leaf, which, generally speaking, is of the better quality of tobacco, is wasted and cannot be employed for making wrappers.

The object I have had in view in making my invention has been to convert tobacco into sheets of larger size than it is in the leaf—that is, such as may be cut up into the proper shape or shapes to be converted into cigar-wrappers—and thus, while I make a more perfect and useful article, I am enabled to use leaf-tobacco of any kind, quality, or size, and convert it into sheets of any suitable size.

In the process of producing my invention I take ordinary leaf-tobacco as sold in the market, and by means or mechanism such as generally adapted for converting rags or various other materials into paper-pulps I reduce the said leaf-tobacco to a pulp, using such a quantity of water or other proper liquid as may be necessary for such reduction. After the pulp has been so formed it is to be converted into sheets, like paper, by the usual means or mechanism generally employed for making into paper-pulp from rags. In other words, I make

from the tobacco-leaf what may be termed a "tobacco-paper," although it is not intended to be used as common paper is ordinarily employed, but is for the special purpose—that of constituting part of a cigar—as above set forth.

I have found that a superior article of cigar-wrapper may be thus manufactured and with great economy and advantage. I would also remark that instead of converting the tobacco pulp directly into sheets it may be formed in a mold or worked up as papier-maché is usually wrought, although I do not consider this latter mode of forming a cigar-wrapper so advantageous as that of reducing the pulp into the form of thin sheets of any desirable length or size.

I do not claim any process of making paper; nor do I claim constructing or making cigar-wrappers in the ordinary and well-known manner out of a leaf of tobacco in its natural and cured state, nor the making of paper out of tobacco stems or stalks, nor the admixture of tobacco with paper-pulp; but

What I do claim is—

A new article of manufacture for the special purpose as above set forth, the same consisting of tobacco-leaf reduced to pulp and subsequently converted into sheets or other desirable form suitable for use, or in the making of cigar-wrappers, as explained.

In testimony whereof I have hereunto set my signature this 13th day of August, A. D. 1857.

FRANCIS DIXON.
